[57] CLAIM

The ornamental design of a multi-container package, as shown and described.

DESCRIPTION

FIG. 1 is a top and front perspective view of the multi-container package;

FIG. 2 is a top view thereof;

FIG. 3 is a left side view thereof, the right side view being a mirror image;

FIG. 4 is a front view thereof, the rear view being identical; and,

FIG. 5 is a bottom view thereof.

The broken line showing of the letters on FIGS. 1, 2 and 5 is for illustrative purposes only and forms no part of the claimed design.

The broken lines shown between the individual containers on FIGS. 1, 2 and 5 represent tear lines.
